(57) **CLAIM**

The ornamental design for a tank, as shown and described.

DESCRIPTION

FIG. 1 is a perspective view of a first embodiment of a tank showing our new design;

FIG. 2 is a right end view thereof;

FIG. 3 is a left end view thereof;

FIG. 4 is a front view thereof;

FIG. 5 is a rear view thereof;

FIG. 6 is a top plan view thereof;

FIG. 7 is a bottom view thereof;

FIG. 8 is a perspective view of a second embodiment of a tank showing our new design;

FIG. 9 is a right end view thereof;

FIG. 10 is a left end view thereof;

FIG. 11 is a front view thereof;

FIG. 12 is a rear view thereof;

FIG. 13 is a top plan view thereof; and,

FIG. 14 is a bottom view thereof.

The first embodiment depicted is shaded to designate that it is opaque. In the second embodiment of the design, the body of the tank is translucent.
